UNITED STATES PATENT OFFICE.

ADRIAN O. VAN DERVORT, OF TROY, NEW YORK.

PACKING-BOX FOR PISTON-RODS.

1,350,046.

Specification of Letters Patent. Patented Aug. 17, 1920.

Application filed October 22, 1919. Serial No. 332,408.

To all whom it may concern:

Be it known that I, ADRIAN O. VAN DERVORT, a citizen of the United States, residing in Troy, in the county of Rensselaer and State of New York, have invented certain new and useful Improvements in Packing-Boxes for Piston-Rods, of which the following is a specification.

This invention relates more especially to 10 means for packing the piston-rods of high-pressure steam engines, and a principal object of the present improvements is to furnish for use on superheater locomotives a packing box of a simple character and a 15 few parts, and which shall provide for effectively meeting the peculiarly exacting requirements appertaining to said classes of engines. A further object is to accomplish the foregoing object and results by means 20 whereby the packing ring shall be relieved (as hereinafter more fully explained), of certain strains normally inimical thereto, and shall be subjected without material detriment thereto, to a progressive and re-formative action during the gradual wearing away thereof, and thereby maintain in a 25 continuous manner the high efficiency which is particularly needful in said service.

In the accompanying drawings forming 30 a part of this specification, Figure 1, is a side view of a packing box made in accordance with my present invention, the portion above the upper line of the rod being in section.

35 Fig. 2, is an end elevation as seen from the left-hand in Fig. 1, but with the usual retaining cap partly broken away, thereby showing the vibrating-casing; this casing is also shown partially broken away to show 40 in side view the upper part of the packing ring, which is contained within a packing ring chamber in the interior of the casing.

Fig. 3 is an enlarged view of a portion of Fig. 2, and shows an upper part of the 45 vibrating casing, an upper part of the rod, an upper part of the two ring segments, and these joining by lapping ends at a chamber, which is within the casing wall.

Figs. 4, 5, 6, 7, 7^a, 8, 9, 9^a, 10, 11, 15, 16, 17, 50 18 and 19 are a series of diagrammatic and explanatory views illustrative of various details and functions as hereinafter more fully described.

55 Fig. 12, is a plan view of the two-segment ring as employed in a preferred embodiment of my invention, and in lapping relation.

Fig. 13, is a plan view showing a plurality of more than two ring segments and in lapping relation.

Fig. 14, is a plan view of a single-member ring the coactive ends of which are in lapping relation.

The embodiment of my invention herein illustrated comprises the retaining cap B, the vibrating-casing C, the spring actuated 65 follower D, the packing ring E, preferably in two segment form, and the rod R.

The ring-chamber or space, is preferably formed within a member, which is arranged to have a movement in directions laterally 70 of the rod when the rod (operating in a well-known manner, and from unavoidable causes), is deflected, or sprung sidewise. This mode of action, or vibratory movement (which is often both rapid and intense), is 75 provided for in the form of construction shown in Figs. 1 and 2, by means of the usual flange and suitable holding means therefor. The ring-inclosing member when thus supported for the described sidewise 80 movements is commonly designated as "the vibrating case," heretofore denoted by C, it being intended for use on piston rods which ordinarily, and almost constantly while in operation, are subjected to a considerable 85 amount of lateral vibration.

Since said vibrating-ring-case C, which comprises a hoop-surface 2° necessarily, in practice, has an internal diameter greater than the external diameter of the rod,—in 90 order to slide freely over the rod,—and since the packing ring is necessarily kept closed-in to fit the rod tightly, (to prevent leakage), therefore, as will now be evident, a lateral movement of the rod acts initially 95 against the metal of the ring, in the present instance a moldable metal, and thus moves the case itself. Thus, in practice, it may be said that the rod operates as an impact device or member, and so tends to drive outwardly the ring-metal—first on one part and then on another part of the circumference of the ring,—and thereby facilitates and accelerates the re-formative action in the case of a moldable ring to which the 105 ring is simultaneously subjected by the steam-pressure, heat and friction.

The packing-ring E especially for the more usual requirements, may be formed of two similar segments, as 2° and 3°, Fig. 12, 110 which together extend entirely around the rod R. These segments each have one end

of a different construction from the other end, but constructed for a novel and effective coaction by a peculiar method and principle.

5 Thus, reference being had to Fig. 12, the right hand segment 2^e is provided as shown, at substantially the upper point of vertical diameter of the packing ring E when in packing position, with an overlapping end 2^f , and at the lower point of vertical diameter of the packing ring E with a projecting end 2^g , and the left hand segment 3^e is provided with an overlapping end 3^f , and at the upper point of vertical diameter 10 of the packing ring with a projecting end 3^g , the segments 2^e and 3^e being coactive in relation to each other.

A chamber G, which for purposes of description I term a relief chamber, is formed 20 at substantially the upper point of vertical diameter of the packing ring E, as shown in Fig. 12, by a portion of the vibrating case C, indicated by the dotted line, the curved portion of the overlapping end 2^f 25 of the segment 2^e , and a portion of the projecting end 3^f of the ring segment 3^e . A similar relief chamber is formed at substantially the lower point of the packing ring E, by a portion of the vibrating case C, the 30 curved portion of the overlapping end 3^f of the ring segment 3^e , and a portion of the projecting end 2^g of the ring segment 2^e , the purpose of the relief chambers G being hereinafter explained.

35 Said coacting segment ends, as 2^e and 3^e (Fig. 12) may be considered as constituting, respectively, the ends of a pair of coacting levers. For instance, in Fig. 3, the left-hand segment-end 3^e , has bearing at point 3^h which is in the nature of a fulcrum, with relation to which that portion of said end 3^e at the right-hand of the radial line 3^i , constitutes a projecting lever-end the outward movement of which is prevented by a 45 force or resistance that is limited to such fulcrum point. Similarly, the right-hand segment-end 2^e has a bearing at the point 2^h , which is in the nature of a fulcrum in relation to the adjoining portions of said 50 end 2^e , when this is considered as functioning after the manner of a lever. These relations and their proportionate effects are indicated in Fig. 3, by dotted lines which also illustrate certain geometrical, or kinematic relations in the preferred form of embodiment of my present improvements, and are later referred to.

55 The diagram Fig. 4, illustrates a preferred construction which in superheater locomotives, and with the packing-ring segments, 2^e and 3^e , made of a composition substantially one half copper and one half lead,—has been found in practice to be particularly advantageous. In this view the 60 arcual extent or length (circumferentially

of the ring) of the overlap of segment ends 2^f and 3^g , is shown by the arc line k^2 , and the arcual length of the relief chamber G, by the longer arc line k^3 . The two engaging faces of said segment ends 2^f and 3^g , 70 respectively, are of equal lengths, and the tip, or point 3^l of said underlapping segment-end, or wedge-end 3^g , is held down in a positive manner against the rod-surface by a reaction force applied to the 75 wedge-point at 3^l in the direction of the line k^4 , which is at about right-angles to the engaging face line of the ring-segments. These geometric relations, bring the center-point of said engaging faces of the segment-ends, in a line, k^5 , which is substantially central of said arc k^3 , so that the two arcual lengths k^2 and k^3 may be said in this 80 instance, to be symmetrically disposed, or arranged.

85 As shown in said Fig. 4, the entire face-line of said underlapping segment-end 3^g (when said engaging faces are true planes), extends from said wedge point 3^l to the point 3^h on the outer circle and is thus considerably longer than the portion thereof which normally engages the coacting face, of said overlapping segment-end 2^f . In this arrangement, and owing to the position of said pressure-line k^4 , the extreme point, as 90 3^l , of the under segment-end 3^g , is prevented from being deflected or bent upwardly from the piston-rod, by a reaction force or resistance acting directly through the body portion of the segment 2^e , and therefor not 100 tending to bend upwardly the projecting lever-end portion 2^f of this segment 2^e ; thus the proper functioning of this overlapping segment-end, 2^f , is materially favored as regards the re-forming action to which these 105 segment-ends are subjected. In this form of the construction the lines forming the angle K, make such angle of about 45 degrees, which results in the segment-end 2^f being sufficiently obtuse to afford a proper 110 resistance, while not unduly resisting the re-forming of the segments under the combined action of heat and pressure, and the friction and vibration of the piston rod.

115 A further feature of the preferred construction shown in Fig. 5, is a symmetrical arrangement of the center-point, as g^6 , of the shaded normally unstable portion, of the segment-end 3^g , with relation to the two fulcrum points 2^h and 3^h of the segment-ends 2^f and 3^g , respectively. The line g^2 drawn through the point 3^h to the central radial line, subtends the angle V^{20} with relation to the central radial line and a similar angle V^{21} is subtended by the line g^3 drawn through the point 2^h to the radial line. In this arrangement if an outwardly-acting force be applied, or centered, at the point g^6 such force will be transmitted 125 through the metal of the coactive segment- 130

ends and to the tension-hoop 2^e of the vibrating case C, and if directly so transmitted such forces would naturally and mainly follow the divergent lines g^2 , g^3 , and 5 be sustained by said hoop at the points 2^h , 3^h . However, the metal between the three points g^6 , 2^h and 3^h may be said to be arranged on the principle of an inverted arch, of which the bases are at (or near) points 10 2^h , 3^h and the crown of the arch is at point g^6 ; the proximate transmission and distribution of the forces and pressures thus sustained are diagrammatically indicated by dotted arch-lines g^4 and g^5 . This diagram, 15 therefore, illustrates how the total amount of work is performed a part by one method and means, and a part in a different way, since the overlap-end or lever-end 2^f is here shown as substantially unaffected by such 20 forces as may be transmitted in the zone between said arch lines. Thus any weakening of the packing ring considered as a whole, which might seem, apparently to be due to the presence of the relief chamber 25 G, is clearly overcome or avoided by the peculiar manner in which the described devices are organized and the highly effective mode of action thereof.

In Fig. 5 that portion of segment 2^e which 30 lies between said arch-lines g^2 , g^3 , constitutes, in effect, a directly-acting compression member or brace between the extreme point-portions, or zone of the projecting end 3^g of the segment 3^e , and the hoop surface 2^e at 2^h ; this being also the fulcrum 2^b 35 of the overlap end 2^f , when this is considered as a lever-end, as more fully explained in connection with Fig. 3. During the wearing away of the metal while the packing box 40 is in use, said brace-forming portion is normally maintained in length by the reforming of the segments, already described. Said point portion or zone of the projecting end 3^g of its acute-angle form, is found in practice 45 to be of insufficient strength for itself resisting outward flexure, and to require a bracing means of a powerful character for holding the same in place; such means is effectively supplied by the construction 50 herein explained.

In the mode of action here described (Figs. 8 and 10), one important feature is not fully shown in any one view, but is evident from all the diagrams and sectional views when these are duly compared:—The 55 lever-end 2^f on being slid forward and forced upward as in Fig. 10 and when this is done (as usually may happen) while the packing ring metal is highly heated and 60 hence relatively mobile and flexible,—the follower D Fig. 1, is forced back by the coaction of said lever-end 2^f with three faces, 3^k , 2^j , 2^d (all relatively inclined each 65 to the other) with the result of bending upwardly the lever-end, while the main por-

tion of the ring-segment is held closely down to the rod, this action being permitted by the relief chamber G. If, now, said lever-end 2^f , retracts to the position indicated by dotted line in Fig. 10, a normal result 70 would be to leave said lever-end bent upward to the position indicated by solid line in Fig. 10, but at this time the follower by acting against the conically formed side surface 2^d Fig. 8, of the ring-segment in the 75 lever-end portion thereof, coacts with the casing cone-surface 3^e and thus strongly tends to rebend said lever-end back to its position shown by said dotted line. Thus the described reformative action or process, 80 when carried into effect by the means herein set forth, comprises a restorative element which being often repeated, tends to prolong the life of the ring-segments.

In Fig. 9, the underlapping end, 3^g , of a 85 ring-segment 3^e , is shown located within the strain-band 2^e (here only partially shown), so that the extreme fulcrum-point 3^h indicates how that band normally resists any outward movement of the projecting wedge-end 3^g , of said segment, due to the action 90 of steam (or other hot fluid) tending to force its way between the surfaces at r^2 ,—that is, between said wedge-end and the surface, indicated by line r^3 , of a piston-rod R. 95 Under these conditions, and for the uses already stated, it is found in practice, that the metal in the shaded zone, is normally non-stable, being too weak for resisting rapid deformation due to the causes herein 100 explained.

The curved line, (Fig. 9), is deemed to closely approximate the boundary,—as occurring most commonly in these rings as used in recent locomotive practice,—between 105 the normally stable and the normally non-stable zones, of the end 3^g of the underlapping ring segment. The extent of said non-stable zone, along the face-line 3^k , of said end 3^g is ordinarily about two-thirds, or not 110 less than one-half of said face line, as indicated by the distance line n^5 , Fig. 8, and hence this distance along said face-line must be held in place by some coacting means, but this means must be so positioned and 115 conditioned as not to interfere with the required gradual reduction and continually-reforming action which should take place slowly during the life of the packing ring.

The lever-like function, or mode of action, 120 is shown in a diagrammatic manner in Fig. 3. The radial line 4^l , extending through said fulcrum point 2^h , may be said to show that the left-hand end portion 2^f of the segment ring 2^e constitutes one end of a lever 125 the other end of which is comprised within the mass of metal at the right-hand of said line. That is, this mass of metal in that part of the segment 2^e , is necessarily an excess over the requirements for a mere lever- 130

action, owing to the well-known parabolic principle, as regards the normal proportions of lever ends, or arms. For indicating this feature, the dotted lines are drawn in Fig. 5 to show how a right-hand lever-arm might be fulcrumed at said point 2^h , and resisted at its end by the rod-surface r^3 at point r^4 . In practice, of course, the forces and strains transmitted by the projecting lever-end 2^e 10 to the right-hand of said line 4^e , will not be actually centered or applied at any one such position, as r^4 , but will be transmitted throughout a more extended portion of the metal, and thus, in one sense, be dissipated 15 through the entire mass. It will be evident, however, that said overlapping segment-end 2^e has the same lever-like character and function, as if it were provided with an opposite lever-arm such as represented by said 20 dotted lines.

This peculiar mode of action is rendered feasible, it will now be obvious, through the provision of the relief chamber G , whereby the described outward movement of the overlap-end 2^e is producible by the coaction of the three pairs of coacting and inclined faces, and is unopposed except by its said inclined faces 3^e , 2^d , Fig. 8, and the only moderate resistance to flexure of the segment due to 25 the character thereof. A feature of this mode of action which is deemed especially important, is that of relieving the ring from an excessive resistance to lengthening, (or, circumferential expansion) at the time, 30 when, (the packing box as a whole being relatively cool), high-pressure steam,—especially superheated steam,—is admitted to the engine cylinder. The normal effect of such conditions is obviously to quickly expand 35 the packing ring, (this expansion being accelerated by the high heat-conducting capacity of the copper therein), and thereby temporarily but suddenly to subject the metal of the ring to a heavy compressive or 40 crushing action. This action as I have discovered tends greatly to accelerate the otherwise slow but constant rate of progress of the well-known disintegratory action, or process, to which such packing-metals, notwithstanding their practical superiority in 45 other respects,—are unavoidably subject.

The arcual length, as V^{21} Fig. 5, of the relief chamber G , may be varied in practice and to some extent, in accordance with 55 the varying requirements in different cases, but a range of lengths of from one and one-half to three times the arc, V^{20} , occupied by the overlap face 2^e , is deemed sufficient for all ordinary requirements; but in the practical demonstrations thus far made, I have 60 found it advisable to make said arc, V^{21} , not less than twice the length of said arc V^{20} , when using packing-metal of the composition stated.

65 Alongside the contacting portions of the

joint faces 2^e , 3^e , Fig. 10, the inclined enclosing walls 3^e , 2^d , are effective, of course, only for the diametrical height as y , Fig. 9, which practically coincides with that of the face-line as V . Thus the entire overlapping wedge-point, or zone 2^g , which is at right-hand of radial line 1^e in Fig. 9, consists of the relatively non-stable portion of the segment-end 3^e , which may be said to be inclosed,—as if in a box,—by these several 75 walls or faces; at the left-hand by the more stable portion of said segment end, (at about the line 1^e), the rod-surface r^3 , the two inclined side walls 3^e and 2^d , and the face as V of the overlapping lever-end 2^e . 80

In thus retracting, or driving back the follower D , the overlap-end 2^e in advancing upwardly on the wedge face 3^e , as already indicated, (acts after the manner of a wedge) operating in two directions and for 85 retracting the follower, but this action, or the pressure due thereto, is normally concentrated, initially, or during such follower retracting, upon a small area of the cone-surface, the center of this area being at 90 about the point o , (Fig. 10), so that the metal of said overlap end is thus naturally subjected to a localized compressive action of greatly increased intensity and thereby tends (owing to the described mobile character of the metal) materially to accelerate 95 the reforming of said portion, 2^e , of the ring or segment. As a result of these complex conditions,—and when the packing-box is in use under heavy steam pressure,—100 the overlap-end 2^e after being forced forward into the relief-chamber G , (as explained in connection with Figs. 8 and 10), rapidly reforms into a modified shape, and this is accomplished in a manner further 105 indicated in Fig. 15, the outline of said parts as shown in Fig. 11, being here shown in dotted lines for the purpose of comparison.

It will, of course, be understood, that 110 said Figs. 10, 11 and 15, are drawn (in order to facilitate comparison), to show an amount of said reforming action which does not, ordinarily or always, take place as one instantaneous shift or change, but which 115 may proceed in a gradual manner, so that the relations shown in Fig. 3 may gradually change to those of Fig. 15 without a distinctive development of the intermediate stage as especially shown in Fig. 11; in this 120 case, said intermediate position or arrangement may be said to be progressively transformed as rapidly as formed, so that while occurring and being effective, it is not a clearly distinguished intermediate arrangement.

However, when the change of temperature and pressure conditions occurs quickly, the overlap-end 2^e may be forced upwardly into the relief-chamber G more rapidly than said 130

reforming action can follow, so that for a brief time a space, as 2^k , (Fig. 10), may be opened between said end 2^f and the rod surface large enough for steam to flow between. 5 This result, when it thus occurs, operates to heat that part of the ring with great rapidity, and thus operates to accelerate the reforming of the coactive ends 2^f 3^g into a newly perfected form and bearing of 10 the modified arrangement, or proportions as illustrated by Fig. 15, and thereby rapidly close said steam outlet or leakage at said space 2^k .

With the packing-rings constructed of 15 about the proportions as shown in Figs. 1, 2 and 3, and used on high-pressure locomotives, it has been found that under the conditions here explained, (and the ring-metal being copper and lead, very nearly one-half 20 of each), the original width, w^2 , Fig. 8, is gradually reduced to the narrower width, as w^3 , while the height, n^5 , is maintained the same as at first and the original relief-chambers G were little if any more than 25 one-half filled up. Furthermore, it was found that the rod packing function was continuously maintained in a highly effective manner, while the usual final breaking-up,—or disintegration,—of the ring-metal 30 was materially delayed in proportion to the service rendered. These valuable results are believed to result from or to be materially enhanced by a peculiar mode of action by means of which the follower ring D is temporarily forced back at a certain time, by a 35 temporary increase of the aforesaid overlap, already referred to in connection with Fig. 15.

Referring, now, to Figs. 10, 11 and 15, it 40 will be evident on comparison thereof, that when the overlap-end 2^f is forced upwardly on the face 3^k of the coacting segment end 3^g the inclined side faces at 3^e , 2^d , of said overlap-end will be moved outwardly; this 45 action is diagrammatically illustrated in Fig. 7, where said 2^f is shown advanced through the distance s , the corresponding outward movement of the side-faces 3^e , 2^d , being shown in Fig. 7^a by the distance t . 50 To accommodate these surface-portion changes, the follower D normally moves back by the corresponding distance t^2 , (see Fig. 7), being forced in that direction by said overlap-end 2^f , acting outwardly, 55 after the manner of a wedge), against the forward incline 3^k as an abutment, and thus operating as an actuator against said follower face 2^d . Thus the two segment faces operate to force outwardly the overlap-end 60 2^f , while this, by its faces forces apart the inclosing faces 3^e , 2^d , thereby retracting or moving back the follower D in the manner and for the purposes herein set forth.

When the packing ring has been employed 65 under conditions as above explained, a fur-

ther result of importance has been found to occur, in practice as regards the favorable manner in which the inner ring surface conforms to the rod surface during the described progressive narrowing and reforming of the ring. In Fig. 6, said inner surface is indicated (in accordance with observed results) as closely bearing on the rod R in two zones n , n^2 , whereas in the mid-zone n^3 said surface, (as seen in the cross-section), is upwardly curved. Thus a space, or a zone of low pressure, appears normally to be formed between the two zones n , n^2 , so that in operation the rod is packed in two separated annular zones between which the lubrication material may collect in sufficient quantity to materially improve the quality of the action and the durability of the co-acting members. 70 75 80

The results and mode of action here explained are believed to be due to some cause not as yet fully understood, but I apprehend that the progressive reforming of the ring metal, as to the width thereof as seen in cross-section, (see Figs. 6 and 18), may take 85 place in connection with lines of force, or pressure-lines, having an arrangement indicated by the lines x , x^2 , in Fig. 18. By this means, and the co-action thereof with the relief from circumferential compression afforded by the relief chambers G , the crushing action due to the pressure of follower D is believed to be diverted,—in the mid-width zone indicated,—to a considerable extent outwardly, thereby causing the outer 90 part at n , n^2 to be kept up to a full size or diameter, as limited only by the inclosing hoop or casing-band 2^e . Thus the inner 95 mid-portion at n^3 appears to be in a normally low-pressure condition favorable to 100 the peculiar mode of action here described. And thus the behavior of the metal while the ring is in service, differs in a radical manner from rings of similar section as used in the old kinds of packings: in these, as is 105 well-known, the wear extends practically uniformly, over the entire inner surface of the ring-member.

The precise manner in which the movement, or "flowage" of the metal probably 110 occurs within the mass, or body, of the ring, is not as yet fully understood, but from a study of observed results of numerous instances of the rod-packing used on locomotives, it clearly appears that owing to the 115 low circumferential compression and the relief obtained by means of the relief chambers, (as specially described in connection with Figs. 10, 11 and 15), the metal is further relieved of restraint as regards the 120 flowage thereof in planes transverse to the ring, and is thus enabled, or permitted, to continually readjust itself for replacement of metal worn away by the rod, in said zones n , n^2 . And, it also appears that under the 125 130

complex conditions above indicated, such worn-away metal is mainly supplied or replaced, by a flowage inwardly of the metal in the mass adjacent to the inclined faces 5 3^e 2^d . This mode of action seems to be favored by some force-line action as indicated by arrow-lines z and z^2 Fig. 17, showing how such an inward movement of the metal at z and z^2 may be in directions nearly vertical to opposing faces at 3^e and 4^e respectively.

As a result of practical investigation, it appears that the line n^e (see Fig. 8) indicates, approximately the manner in which 15 the side portions tend slowly to move inwardly under the continued co-action of the wear and the pressure, and of the friction, and heat while in use. This action operates, it seems evident, in wearing away most rapidly, the outer zones, of the inner face of the ring, so that the relative wearing away of the face may be indicated by a reversely-curved line n^7 , (Fig. 8). This wearing away 20 of the ring-metal is compensated for, gradually during the reduction of the mass of the ring in part by a tendency of the ring to close inward to a smaller diameter under the action of said inclined end faces 3^e , 2^d , and further, by a slow but effective reforming 25 of that mass as to its cross-sectional proportions. For instance, if the ring metal should be worn away to the extent shown by line n^7 , in order to maintain both the outer and inner diameters thereof, the length of 30 said cross-section (Fig. 8) would have to be shortened to the amount shown by line n^8 ; and in practice, this reformation seems actually to occur; the described shortening being in the nature of a secondary action 35 which continuously follows said gradual mass reduction as effected by the wearing away of the inner zone of the cross-section.

The aforesaid modes, of action, or effects, 40 while believed to be concurrent and continuous, apparently are not at all times of precisely the same ratio; furthermore, in accordance with principles well understood, the metal on the inner surface, as at n^7 appears to tend to move (under said reforming action) or broaden out, not only lengthwise 45 of the piston, but also circumferentially thereof, thereby tending to lengthen the ring segments, with the result of sliding forwardly the overlapping end 2^e , as indicated 50 by the solid-line position thereof in Fig. 11. This movement, however, is opposed by the compressive and wedging-in actions of the faces 3^e , 2^d ; but this opposing action is limited in its effect by the relatively low power 55 of resistance of the ring-metal while in a heated condition, so that, in practice, the extent, of said overlapping is found to gradually increase, especially under severe service, but not to such an extent as to

entirely fill the relief-chamber space, G 65 (Fig. 15).

These complex actions and reactions evidently have from time to time, different ratios; or degrees of co-action, under the widely and rapidly varying conditions of use. For instance, the ring-segments 2^e , 3^e , when heated, more quickly than the inclosing-hoop 2^e , (as must often occur in locomotive practice) tends to lengthen and thus increase said overlap distance, which, later and normally would be reduced. Thus, the relief-space at G permits of a temporary and excessive overlap deformation of said overlapping ends 2^e , 3^e of the segments, this result being one of importance as regards the "life" of the ring.

These effects are further modified or limited, by the inclosing hoop 2^e . This member is necessarily a strong and stable one, and hence is preferably made of steel, or of a rigid metal highly contrasting with that of the ring-segments; and, hence, in practice, said hoop member will ordinarily have a ratio of expansion by heat, much less than that of the ring-metal.

In Fig. 9^a, dotted lines are drawn for indicating a series of zones in the lever end 2^e , and, in the wedge-end 2^s ; and are shown curved in arrangement for suggesting the manner in which metal of similar forms, and especially when considerably heated, tends to flow, or be driven off, when subjected to a sufficient intense and concentrated pressure. Said zones, as thus drawn run from a normally stable zone, as t^3 , at one end of a series, to a normally unstable zone, as t^4 , at the other end of the series. Thus the stable zone t^2 of the lever-end 2^e is complementary to the unstable zone t^4 of said wedge-end; and, this complementary relation extends to the other pairs of the two series, as clearly shown by this diagram, since said series of zones are progressive from the maximum to minimum stability in opposite directions, respectively, so that a more stable zone of one series coacts with a weaker, or less stable zone of the other series. Thus all of these zones are so related as to produce nearly equal co-acting pairs of them, as regards their stabilities.

In Fig. 15, the successive dash lines (x^3 , x^4) further indicate the nature of the progressive reformation of the overlapping lever-end portion 2^e , during a considerable period of use. At first, the fulcrum point being at about the point 2^h , the segment-end 2^e bears on the wedge-end 3^s only up to the point x^5 , but as the reformatory action progresses, this bearing extends slowly upward, and the fulcrum point moves along toward the center-line as for instance, to the point 4^h ,—thereby reducing the freedom of action, and of co-action for the required function-

ing, to such an extent that the packing-ring should then be replaced by a new one.

In the form and proportions thereof as shown in Figs. 10, 11 and 15, the lever-end portion of the segment 2^f has its fulcrum point, as 2^h, in such a position that a line, as h^7 Fig. 9 therefrom, is vertical to the plane of the wedge-end face, 3^g (of the co-acting segment-end 3^e) at a point at or near to the inner end of said face. Also, it will be noted that the underlapping end 3^g, has an outer zone at h^8 of the inclined face thereof, free from contact with said overlapping lever-end 2^f, but so arranged that the latter member can slide outward therewith, during successive stages of the expanding and contracting movements to which, (as already explained in connection with Figs. 10, 11 and 15) these members are repeatedly subjected while in use, and during the reformative action to which the packing-ring metal is subjected.

When the packing ring is intended for use with locomotive piston-rods of ordinary sizes, and for use under temperatures of from 400 to 700 degrees, (Fahr.), and is composed of the described "half and half" mixture of copper and lead, I have found that a favorable position, or angular relation to the two contacting faces 3^k, 2^j Fig. 10 of the underlapping and overlapping ends 3^g, 2^f, respectively, may be suitably proportioned by making said faces in a plane,—as shown in Fig. 19,—coinciding with a chord-line m which is so positioned that the chord (from point m^2 to point m^3) of the outer circle is twice the length of the chord (from point m^4 to point m^5) of the inner circle. This construction makes the distance m^6 equal to the distance m^7 , and this is also the proportion as shown in Figs. 2 and 4, but those proportions may be varied.

The provision of the necessary relief-chambers may be effected, in practice, in two ways, preferably as in Figs. 12 to 14, inclusive, and in some instances as shown in Fig. 16. In the construction illustrated by Figs. 12 to 14, inclusive the packing ring regardless of the number of segments comprised therein,—is free to gradually work around, or turn within the packing-ring chamber, which is deemed to be desirable, since this action clearly tends to equalize wear and strains. However, to provide for said chambers the necessary room by this construction, the thickness of the ring segments,—diametrically of the ring,—is preferably made greater than otherwise would be essential.

In Fig. 16 the relief-chamber, G², is shown located as before inside the hoop 2^e, but is here located in a position exteriorly (instead of interiorly) of the inner circle thereof, and the ring segments 2^e, 3^e are of a reduced thickness. In this case, how-

ever, the fulcrum points, as 2^h, 3^h are related both as to position and function,—to the co-acting segment-ends 3^g, 2^f, in the same manner as already explained in connection with Figs. 3 and 12; this is further indicated by the diagram lines of Figs. 11 and 15 as reproduced in this view. In this construction (Fig. 16) it is, of course, necessary to provide means for preventing the circumferential slipping out of place of the segments; this may be done by using an ordinary dowel-pin, as P, preferably placed about midway of the length of each segment.

The number of segments comprised in a complete packing-ring, may vary in different instances, according to requirements. For instance, in Fig. 12, two segments 2^e, 3^e, (preferably duplicates) are shown, each having one lever-end, as 2^f, or 3^f overlapping a wedge-end, as 3^g or 2^g of the companion segment, and there being a relief-chamber G, at each such pair of co-active segment-ends, when the ring is assembled in the packing box.

In Fig. 13, a multiplex construction is shown, comprising the three duplicate segments such as 2^e, 3^e, and each segment having a lever-end and an underlapping wedge-end, all arranged and co-active in the manner illustrated in Figs. 10, 11 and 15, already described. A particular advantage of such a larger number of segments (more than two), is that the effect of the yielding and reformative actions described in connection with Figs. 10, 11 and 15 is multiplied, thus providing for the requirements of extreme cases, as for instance, for use on large piston rods which are subjected to unusual changes of temperature or of steam-pressure, or both.

In some instances, the packing ring may be a single-piece member and one such form is illustrated in Fig. 14. In this case, however, the ring may still be regarded as comprising two segments, as 2^e and 3^e, integrally joined at the dotted line and co-actively joining each other at the relief-chamber G, where the lever-end 2^f and the wedge-end 3^g are arranged and function in the manner explained in connection with said Figs. 10, 11 and 15; accordingly this understanding of said construction of Figs. 10, 11 and 15 has been adopted in and for the purposes of this description.

By a comparison of the several diagrams and the foregoing explanations thereof, it will now be evident how the packing-ring comprises segments joining,—at each segment-lap thereof, by a pair of lapping segment-ends (as 2^e, 3^e, Fig. 3) one of which, as 3^g, is underlapping and the other of which, as 2^f, is overlapping; and, how said segments,—these being composed of a compound of metal of suitable resistance to reformation,—are slowly reformable in

cross-section under the combined action of the described follower-ring pressure and heat while subjected to the friction (and, of course, to the resistant surface and pressure) of a moving piston-rod to which the 5 packing box shall be applied; and how said action and results take place in connection with a relief-chamber, (as G, Fig. 3) formed or walled-in, by and between the segment-10 lap portion of the packing-ring and the inside surface of said tension-hoop, this relief-chamber having an arcual length, circumferentially of the packing-ring, for permitting an extension of the lapping of the 15 segment-ends by a reforming (see Figs. 10, 11 and 15) of the overlapping segment-end, as 2¹, during such a closing-in of the packing ring as may be required for compensating any loss of packing ring substance or reduction of mass, due to wear, or 20 otherwise occurring.

The proportions of the copper and lead components in a copper-lead packing ring may be varied, in practice, to some extent 25 without preventing the proper mode of action of the ring; and it should be understood that small quantities of other metals or substances, in the nature of adulterants, may be present in the copper-lead composition 30 without destroying the reforming capacity thereof. In the case of some of those compositions, it appears that a slight reduction of mass may gradually occur by reason of oxidation or other chemical action, 35 and also by a kind of compacting together of the ingredients when the mass, as initially formed, has some degree of porosity. Thus the packing ring when put into actual 40 service may have, or be subject to a loss (usually relatively small in amount) of substance or reduction of mass of volume, in addition to that directly due to the wearing away thereof by the friction of the steam heated piston rod.

45 Having thus described my invention I claim:

1. In a rod-packing, in combination, an 50 annular packing ring chamber comprising an outer wall forming a tension hoop, and two annular end walls each facing toward the other; a follower ring of which the inner face thereof constitutes one of said end-walls; means for actuating the follower ring in a direction for subjecting a packing 55 ring in said chamber to a width-contracting pressure; and a packing ring in said chamber consisting of co-acting segments composed of a metal mixture moldable under the action of the pressure and heat of super-heated steam, said segments each having 60 one underlapping wedge-end, and also having one overlapping lever-end bearing upon and extending only partially over the wedge-end of a co-acting segment, and the rod-packing having between the tension-hoop and the lapping wedge-end and lever-end, a relief chamber occupying an arcual length circumferentially of the ring greater than the arcual length of the bearing of a said lever-end upon a said wedge-end.

and the lapping wedge-end and lever end, a relief chamber occupying an arcual length circumferentially of the ring greater than the arcual length of the bearing of a said lever end upon said wedge-end.

2. In a rod-packing, in combination, an annular packing-ring chamber comprising an outer wall forming a tension hoop, and two annular end walls each facing toward the other; a follower-ring of which the 75 inner face thereof constitutes one of said end-walls; means for actuating the follower-ring in a direction for subjecting a packing-ring in said chamber to a width-contracting pressure; and, a packing ring 80 in said chamber and consisting of co-acting segments composed of a two-metals mixture moldable under the action of the pressure and heat of super-heated steam, said segments each having one underlapping 85 wedge-end, and also having one overlapping lever-end bearing upon and extending only partially over the wedge-end of a co-acting segment, and the rod-packing having between the tension-hoop and the lapping 90 wedge-end and lever-end, a relief chamber occupying an arcual length circumferentially of the ring greater than the arcual length of the bearing of a said lever-end upon a said wedge-end.

3. In a rod-packing, in combination, an annular packing-ring chamber comprising an outer wall forming a tension-hoop, and two annular end walls each facing toward the other; a follower-ring of which the 100 inner face thereof constitutes one of said end-walls; means for actuating the follower-ring in a direction for subjecting a packing-ring in said chamber to a width-contracting pressure; and, a packing ring in said chamber and consisting of co-acting segments 105 composed of the metals copper and lead proportioned substantially one-half of each of said metal, and segments each having one underlapping wedge-end, and also having one overlapping lever-end bearing upon and extending only partially over the wedge-end of a co-acting segment, and the rod-packing having between the tension-hoop and the lapping wedge-end and lever-end, a relief chamber occupying an arcual length circumferentially of the ring greater than the arcual length of the bearing of a 115 said lever-end upon a said wedge-end.

4. In a rod-packing, in combination, an 120 annular packing-ring chamber comprising an outer wall forming a tension-hoop, and two annular and conical walls oppositely-disposed and outwardly converging; a follower-ring of which the inner face thereof 125 constitutes one of said end-walls; means for actuating the follower-ring in a direction for subjecting a packing-ring in said chamber to a width-contracting pressure; and a packing-ring in said chamber 130

ber and comprising co-acting segments consisting of two-metals mixture moldable under the action of the pressure and heat of superheated steam and comprising the metals copper and lead proportioned substantially one-half of each said metal, said segments each having one underlapping wedge-end, and also having one overlapping lever-end bearing upon and extending only partially over the wedge-end of a co-acting segment, and the rod packing having between the tension-hoop and the lapping wedge-end and lever-end, a relief chamber occupying an arcual length greater than the arcual length of the bearing of a said lever-end upon a said wedge-end.

5. In a rod-packing, in combination, an annular packing-ring chamber comprising an outer wall forming a tension-hoop, and two annular and conical end walls oppositely-disposed and outwardly converging; a follower-ring of which the inner face thereof constitutes one of said end-walls; means for actuating the follower-ring in a direction for subjecting a packing-ring in said chamber to a width-contracting pressure; and a packing ring in said chamber and comprising co-acting segments consisting of a two-metals mixture moldable under the action of the pressure and heat of superheated steam and comprising the metals copper proportioned substantially one-half of each said metal, said segments each having one underlapping wedge-end, and also having one overlapping lever-end bearing upon and extending only partially over the wedge-end of a co-acting segment, and the rod-packing having between the tension-hoop and the lapping wedge-end and lever-end, a relief-chamber occupying an arcual length, circumferentially of the ring of between one and one-half and three times the arcual length of the bearing of a said lever-end upon a said wedge-end.

6. In a rod-packing, in combination, an annular packing-ring chamber comprising an outer wall forming a tension-hoop, and two annular and conical end-walls oppositely-disposed and outwardly converging; a follower-ring of which the inner face thereof constitutes one of said end-walls; means for actuating the follower-ring in a direction for subjecting a packing-ring in said chamber to a width-contracting pressure; and, a packing-ring in said chamber and comprising co-acting segments consisting of a copper and lead composition slowly moldable under the combined action of the pressure and heat of superheated steam and the friction and vibration of a heated piston-rod, said segments each having one underlapping wedge-end, and also having one overlapping lever-end bearing upon and extending only partially over the wedge-end of a co-acting segment, and the rod-packing

having between the tension-hoop and the lapping wedge-end and lever-end, a relief-chamber substantially as and for the purpose set forth.

7. In a rod-packing, in combination, an annular packing-ring chamber comprising an outer wall forming a tension-hoop, and two annular and conical end walls oppositely-disposed and outwardly converging; a follower-ring of which the inner face thereof constitutes one of said end-walls; means for actuating the follower-ring in a direction for subjecting a packing-ring in said chamber to a width-contracting pressure; and, a packing ring in said chamber and comprising co-acting segments consisting of a copper and lead composition slowly moldable under the combined action of the pressure and heat of superheated steam and the friction and vibration of a heated piston-rod, said segments each having one underlapping wedge-end, and also having one overlapping lever-end bearing upon and extending over less than two-thirds of the face-length of a wedge-end of a co-acting segment, and the rod-packing having between the tension hoop and each pair of lapping segment ends, a relief chamber occupying an arcual length circumferentially of the ring greater than the length of the contact of a said lever-end upon the face of a said wedge-end. 70 75 80 85 90 95

8. In a rod packing, in combination, an annular packing-ring chamber comprising an outer wall forming a tension-hoop, and two annular and conical end walls oppositely disposed and outwardly converging; a follower-ring of which the inner face thereof constitutes one of said end-walls; means for actuating the follower-ring in a direction for subjecting a packing-ring in said chamber to a width-contracting pressure; and, a packing ring in said chamber and comprising co-acting segments consisting of a material moldable under the combined action of the pressure and heat and the friction and vibration of a piston-rod, said segments each having one underlapping wedge-end, and also having one overlapping lever-end bearing upon and extending over a portion of the face-length of a wedge-end of a co-acting segment, and the rod packing having between the tension-hoop and each pair of lapping segment ends, a relief chamber extending circumferentially of the ring. 100 105 110 115 120

ber to a width-contracting pressure; and, a metal packing ring in said chamber and comprising co-acting segments, the metal of said ring-segments being moldable under the combined action of the pressure and heat when subjected to the friction and vibration of a piston-rod, said segments each having one underlapping wedge-end, and also having one overlapping lever-end bearing upon and extending over a portion of the face-length of a wedge-end of a co-acting segment, and the rod-packing having between the tension-hoop and each pair of lapping segment ends, a relief chamber extending circumferentially of the ring.

10. In a rod-packing, in combination, an annular packing-ring chamber comprising an outer wall forming a tension-hoop, and two annular and conical end walls oppositely-disposed and outwardly converging; a follower-ring of which the inner face thereof constitutes one of said end-walls; means for actuating the follower ring in a direction for subjecting a packing-ring

25 in said chamber to a width-contracting pressure; and, a packing-ring in said chamber and comprising co-acting segments consisting of a composition slowly moldable under the combined action of the pressure and heat when subjected to the friction and 30 vibration of a piston-rod, said segments each having one underlapping wedge-end, and also having one overlapping lever-end bearing upon and extending over a portion of the face-length of a wedge-end of a co- 35 acting segment, and the rod-packing having between the tension-hoop and each pair of lapping segment ends, a relief chamber occupying an arcual length circumferentially 40 of the ring sufficient for permitting said moldable action of the heat and pressure upon the segment ends, substantially as set forth.
